UNITED STATES PATENT OFFICE.

SAMUEL D. BROWN, OF ANDREWS SETTLEMENT, PENNSYLVANIA.

DESIGN FOR A FILE.

SPECIFICATION forming part of Design No. 28,690, dated May 24, 1898.

Application filed January 29, 1898. Serial No. 668,489. Term of patent 3½ years.

To all whom it may concern.

Be it known that I, SAMUEL D. BROWN, a citizen of the United States, residing at Andrews Settlement, in the county of Potter and State of Pennsylvania, have invented and produced a new and original Design for Files, of which the following is a specification, reference being had to the accompanying drawings, forming part thereof.

10 Figure 1 is a perspective view. Fig. 2 is a longitudinal sectional view.

As shown in the drawings, the leading or material feature of my design consists of a tip B at the outer end of a file A, the body of 15 the file being provided with flat roughened or toothed faces, each of which disappearing at

the handle end in a curved, tapering, triangular, plain surface, all of said surfaces merging into a cylindrical smooth end, the tip being substantially of the shape of an acorn and 20 one of the angles of the file at its junction with the tip being cut away on a curved line, as shown.

Having thus fully described my design, what I claim as new, and desire to secure by 25 Letters Patent of the United States, is—

A design for a file, substantially as herein set forth.

SAMUEL D. BROWN.
